UNITED STATES PATENT OFFICE.

SYLVESTER A. BAKER, OF SAN FRANCISCO, CALIFORNIA.

DESIGN FOR A STREET-LIGHT GLOBE.

Application filed April 16, 1928. Serial No. 26,337. Term of patent 14 years.

To all whom it may concern:

Be it known that I, SYLVESTER A. BAKER, a citizen of the United States of America, residing at San Francisco, in the county of San Francisco and State of California, have invented a new, original, and ornamental Design for Street-Light Globes, of which the following is a specification, reference being

had to the accompanying drawing, forming a part thereof.

The figure is a front elevation of my design.

I claim:

The ornamental design for a street light globe substantially as shown.

SYLVESTER A. BAKER.
